UNITED STATES PATENT OFFICE.

LOUIS P. KOLODGE, OF NEW KENSINGTON, PENNSYLVANIA.

GEOMETRICAL INSTRUMENT.

Application filed October 19, 1926. Serial No. 142,659.

This invention relates to improvements in geometrical instruments, and has more particular reference to an instrument particularly serviceable in numerous operations performed by draftsmen, carpenters and the like, and embodying a square and an adjustable straight edge member.

The primary object of the invention is to provide an instrument of the above kind which is extremely simple and durable in construction and capable of adjustment with facility and ease.

A more specific object of the invention is to provide simple and effective means for maintaining the straight edge member in adjusted position in a reliable manner.

A still further object is to provide an instrument of the above kind wherein the straight edge member, in certain of its positions of adjustment, cooperates with the square for forming a right-angle triangle, of a degree depending upon the adjusted position of said straight edge member.

Other objects will become apparent as the nature of the invention is better understood, and the same consists in the novel form, combination and arrangement of parts herein-after more fully described, shown in the accompanying drawing and claimed.

In the drawing, wherein like reference characters indicate corresponding parts throughout the several views,

Figure 1 is a side elevational view of a combined square and adjustable straight edge instrument constructed in accordance with the present invention;

Figure 2 is an edge elevational view thereof of looking toward the left of Figure 1;

Figure 3 is an enlarged fragmentary sectional view taken substantially upon line 3—3 of Figure 1;

Figure 4 is a view similar to Figure 3 taken upon line 4—4 of Figure 1; and

Figure 5 is an enlarged sectional view taken upon line 5—5 of Figure 1.

Referring more in detail to the drawing, the present invention embodies a square composed of rigidly connected and preferably integrally formed arms 5 and 6 extending at right angles to each other, and an adjustable straight edge member 7 connected one end to the arm 6 so as to be capable of adjust-

ment longitudinally of the outer end portion of the latter as well as capable of swinging relative thereto toward or away from the arm 5 as indicated by dotted lines in Figure 1.

The adjacent free ends of the arm 5 and the adjustable straight edge member 7 are beveled along adjacent edges as at 8 so as to lie in contiguous relation and terminate flush with each other at their free ends as at 9 when the other end of the straight edge member 7 is adjusted to its innermost positions relative to the arms 6, whereby a substantially complete 30 degree right-angle triangle is formed. Obviously, by adjusting the associated end of the straight edge member 7 outwardly relative to the arm 6, substantially complete triangles of various degrees of angle may be formed. Also, by setting the straight edge member at various pivotally adjusted positions toward and away from the arm 5 and relative to the arm 6, various angles of miter or bevel may be engaged.

In order to pivotally and slidably connect the end of the straight edge member 7 to the arm 6, the outer end portion of said arm 6 is rabbeted upon opposite sides as at 9 to provide a portion 10 of reduced thickness which is longitudinally slotted parallel with the outer edge of arm 6 as at 11. The associated end of the straight edge member 7 is bifurcated to straddle the portion 10 of the arm 6, and a clamping screw 12 passes freely through one bifurcation of the member 7 and freely through the slot 11 and has threaded engagement in an aperture of the other bifurcation of member 7. Thus, upon loosening the screw 12 the straight edge member 7 will be free, except as herein-after pointed out, to swing relative to the arm 6 toward and away from the arm 5 of the square or to slide longitudinally of the arm 6 for a distance limited only by engagement of the screw 12 with an end of the slot 11, the latter terminating at its outer end near the outer end of the arm 6 as shown. Moreover, upon tightening the screw 12 the bifurcations of the member 7 may be drawn together tightly against opposite sides of the reduced portion 10 of arm 6 so that pivotal or sliding adjustment of the member 7 rela-

tive to said arm 6 is prevented under ordinary circumstances.

In order to more securely retain the straight edge member in its adjusted positions relative to the arms 5 and 6 of the square, an adjustably extensible connection is provided between the adjacent intermediate portions of arm 5 and straight edge member 7, said adjustable connection preferably embodying a pair of links 13 and 14 which are connected at adjacent ends by a pivot-forming clamping screw 15 so as to be capable of being set and maintained in any desired angular relation, the setting being permitted by loosening the screw 15, and the retention of such setting being effected by tightening the screw 15. As shown, the outer ends of the links 13 and 14 are bifurcated to respectively straddle reduced intermediate portions 16 and 17 of the arm 5 and straight edge member 7, the links being pivoted to these members 5 and 7 at these points as at 18 and 19.

From the above description it will be seen that upon loosening the screw 15 the links 13 and 14 will be freely movable relative to each other for folding or unfolding so that the desired pivotal or sliding adjustments of the straight edge member 7 relative to the square arm 6 may be effected. It will also be seen that upon tightening the screw 15 after the desired adjustment of the straight edge member has been effected, relative movements of the links 13 and 14 will be prevented so that the screw 12 will be aided in its function of retaining the straight edge member in the position to which it has been set.

An instrument constructed in accordance with the above may be adjusted and constructed so as to provide a substantially complete right-angle triangle of any degree between 30 and 60 degrees without being of objectionable size or form. Moreover, when the straight edge member 7 is adjusted relative to the arm 6 and used without reference to the arm 5 of the square, the same may be conveniently employed for gaging bevels or miters or for marking bevels or miter guide lines as is obvious to those skilled in the art. The instrument is capable of use for many operations readily apparent and suggestive to those skilled in the art, so that further description of useful purposes is deemed unnecessary.

In view of the above it will be seen that I have provided a very simple and practical form of instrument of the character described which may be readily plated into practical use and which may be manufactured and assembled cheaply and expeditiously.

Minor changes may be made without de-

parting from the spirit and scope of the invention as claimed.

65

What I claim as new is:—

1. A geometrical instrument comprising a square composed of rigidly connected arms extended at right angles to each other, a straight edge member, means connecting said straight edge member at one end to one of said arms for pivotal and sliding movement therealong, and an extensible connection between the intermediate portion of the straight edge member and the other arm 75 of the square.

2. A geometrical instrument comprising a square composed of rigidly connected arms extended at right angles to each other, a straight edge member, means connecting 80 said straight edge member at one end to one of said arms for pivotal and sliding movement therealong, and an extensible connection between the intermediate portion of the straight edge member and the other arm 85 of the square, said extensible connection comprising a pair of links respectively pivoted to the straight edge member and said other arm of the square at their outer ends and having their inner ends adjustably 90 hinged together.

3. A geometrical instrument comprising a square composed of rigidly connected arms extended at right angles to each other, a straight edge member, means connecting said 95 straight edge member at one end to one of said arms for pivotal and sliding movement therealong, said straight edge member and the other arm of the square having adjacent edges of their free end portions complementally beveled to lie in contiguous relation with said edges in contact with each other when the pivoted end of the straight edge member is adjusted to its innermost position relative to said one arm of the 105 square.

4. A geometrical instrument comprising a square embodying a pair of rigidly connected arms extending at right angles to each other, a straight edge member, means 110 connecting said straight edge member at one end to the outer end portion of one of said arms for pivotal and sliding movement therealong, the means for pivotally connecting said straight edge member to said arm 115 embodying means for securing said end of the straight edge member in any desired position of adjustment when slid longitudinally of said arm, an extensible connection pivotally engaged with the intermediate portions of the other arm of the square and said straight edge member, and means to secure the extensible connection in any desired extended condition.

In testimony whereof I affix my signature.

LOUIS P. KOLODGE.
